C. B. McAULAY.

HYDRAULIC NOZZLE CONSTRUCTION

Filed Feb. 8, 1922

UNITED STATES PATENT OFFICE.

CHESTER B. McAULAY, OF PALO ALTO, CALIFORNIA.

HYDRAULIC-NOZZLE CONSTRUCTION.

Application filed February 8, 1922. Serial No. 534,865.

To all whom it may concern:

Be it known that I, CHESTER B. McAULAY, a citizen of the United States, residing at Palo Alto, in the county of Santa Clara 5 and State of California, have invented certain new and useful Improvements in Hydraulic-Nozzle Constructions, of which the following is a specification.

The present invention relates to nozzle 10 constructions employed in connection with hydraulic installations, and particularly with impulse wheels. It is at present the practice to employ what may be termed a needle nozzle for universal work, i. e. for 15 full loads and for fractional loads, but experience has demonstrated that the true needle nozzle will not operate at maximum efficiency under both fractional load and full load conditions. It has been also demonstrated that the needle nozzle has an efficiency of approximately 75 per cent, while what may be termed the open nozzle has an 20 efficiency of approximately 92 per cent, and it is the principal object of this invention to 25 provide a single nozzle construction which when operating under fractional loads will have the maximum efficiency of a needle nozzle, and when operating under full loads will have the maximum efficiency of an open 30 nozzle. The needle nozzle and open nozzle have characteristics which preclude the possibility of one nozzle operating as both, viz:—the needle nozzle requires a sharp edge 35 orifice and the water issuing therefrom hugs the needle until it combines a solid jet near the needle tip; while the straight or open nozzle forms a channel for the water down to the jet diameter, and is provided with parallel sides for a short length forming a 40 cylinder of the stream or jet diameter.

In my present invention, it is the principal object to provide what may be termed an open nozzle tip movably associated with the discharge end of the outer needle nozzle, and 45 to operate said tip in such manner that under full load conditions the water discharges therefrom in a full open nozzle form, and when discharging under fractional loads will be controlled by the true needle nozzle 50 thus economizing in the water used.

With the above mentioned and other objects in view, the invention consists in the novel construction and combination of parts

hereinafter described, illustrated in the accompanying drawings, and set forth in the 55 claims hereto appended, it being understood that various changes in the form, proportion, size and minor details of construction within the scope of the claims may be resorted to without departing from the spirit 60 or sacrificing any of the advantages of the invention.

To more fully comprehend the invention reference is directed to the accompanying 65 drawings, wherein:—

Figure 1 is a view in side elevation of a nozzle construction for impulse wheels illustrating my improvement in connection therewith.

Figure 2 is a horizontal sectional view 70 through the embodiment illustrated in Figure 1, illustrating more particularly my full open nozzle tip associated with the true needle nozzle, the parts being in a position with the needle closed.

Figure 3 is a fragmentary sectional view 75 of the full open nozzle tip in contact with the discharge end of the needle nozzle, in which position the needle is fully retracted.

Referring more particularly to the several views of the drawings wherein like characters of reference designate corresponding parts, 1 indicates a casing having a water inlet 2 connected with a supply under the desired pressure and said casing 1 at 80 the discharge end of the inlet 2 is reduced in diameter as at 3, and has secured thereto a nozzle 4, the interior wall 5 thereof being of true needle nozzle form. The orifice 6 of the nozzle 4 is controlled by a needle bulb 7 85 having a tip 8 and mounted on a reciprocating stem 9 guided in its movement through a bushed guide or bearing 10 of the well known construction. The rear end of the stem 9 is threaded as at 11, and is received within an adjusting screw 12 held from longitudinal movement within a guide 13, the screw carrying a bevel gear 14 which intermeshes with an operating pinion 15 rotated by the action of the wheel 16. The operation of the wheel 16 reciprocates the stem 9 100 the needle bulb 7 to control the fluid volume passing through the orifice 6. The nozzle 4 and elements up to and including the wheel 16 are of well known construction 105 in the art, and their specific construction and

formation forms no part of the present invention.

Extending radially from the outer wall of the nozzle 4 are the guide arms 17 in rear 5 of which are formed preferably integral with the nozzle 4, the cylinders 18, and in each of these cylinders is mounted a piston 19 carried by a rod 20, the rods reciprocating through guides 21 in the arms 17, and the 10 guides further reciprocating through packing glands closing the open end of the cylinders 18. On their outer ends the rods 20 connect with the radial arms 23 of a nozzle tip 24, the walls of the orifice 25 thereof 15 being in parallel relation and forming what may be termed a true open nozzle. The stems 20 mount the tip 24 so that the orifice 25 thereof is in axial alignment with the discharge end of the orifice 6 of nozzle 4, and the wall of the orifice 25 is adapted to 20 one end to contact with the outer end of the wall of the orifice 6 under certain conditions. In other conditions, hereinafter described, the tip 24 is adapted for movement outwardly in advance of the outer end of the wall of the orifice 6 to provide between co-operating ends of said orifice walls an annular air inlet for the hereinafter described purpose.

To operate the nozzle tip 24 to obtain the maximum efficiency from the nozzle and tip under full and fractional loads, any suitable mechanism may be employed, the embodiment illustrated having been found very efficient, and said embodiment consists in a pipe 26 connected at one end with the casing inlet 2 for receiving water under pressure. The opposite end of the pipe connects with a valve casing 27 preferably in the center and 25 said casing at its opposite end is provided with relief channels 28. A reciprocating controlling valve stem 29 is mounted in the casing 27 and the stem carries spaced controlling disk valves 30. From the casing 27 30 at points corresponding to the distance between the valves 30 extend two pipes 31 and 32, from which extend the respective branches 31' and 32' connecting respectively the branches 31' with the cylinders 18 at their forward ends and the branches 32' with the cylinders at their rear ends. With the outer 35 end of the stem pivotally connects a trip lever 33 fulcrumed as at 34, and the lower end of which is notched as at 35 to receive an adjustable trip finger 36 capable of 40 threaded adjustment on the threaded end 11 of the stem 9.

It will be observed that during the movement of the needle valve to deliver fractional 45 loads from the nozzle, the trip 36 will, dependent on its adjustment, have during its movement a predetermined stroke, tripped the lever 33, and moved the valves 30 to the position illustrated in Figure 2, which enables the pressure in pipe 26 to pass through

pipe 32 and branches 32' operating against the rearward face of pistons 19 causing said nozzle tip 24 to move forwardly with the rear wall of its orifice spaced from the forward wall of the orifice 6. This movement provides a needle nozzle of the true form through which the stream flow issues when the nozzle is operating under fractional loads, i. e. when the needle 7 is moved forwardly to reduce the fluid flow from orifice 6, and affords an annular space between the members 4 and 24 allowing air to enter and break the tendency of the fluid following the contour of the needle to form a vacuum within the orifice 25. On the rearward movement of the needle valve a sufficient distance to enable the fluid to discharge through the orifice 24 under what could be termed full load conditions, the finger 36 trips the lever 33 moving the same forwardly in the 50 casing 27 and connects the pressure pipe 26 with the pipe 31 and branch pipes 31' admitting fluid under pressure into the cylinders 18 in front of piston 19. This pressure forces the pistons rearwardly in their casings and moves the inner edge of the orifice 25 of the nozzle tip 24 into contact with the outer edge of the wall of the orifice 6 of the nozzle 4, forming of said members 4 and 24 55 a true open nozzle for operating under full loads.

I claim:—

1. A hydraulic nozzle construction including a main nozzle member, a tip associated therewith and provided with an orifice for registering with the orifice of the main nozzle member, means for moving the tip to and from the nozzle to provide an air inlet between the nozzle and tip, and a needle valve adapted for controlling the stream flow through the nozzle.

2. A hydraulic nozzle construction including a main nozzle member, a tip associated therewith and provided with an orifice for aligning with the orifice of the main nozzle member, means for moving the tip to and from the main nozzle to provide an air inlet between the nozzle and tip and with the tip orifice in alignment with the orifice of the main nozzle member, and a needle valve for controlling the stream flow from said main nozzle member.

3. A hydraulic nozzle construction including a main nozzle, a tip associated therewith and provided with an orifice in register with the nozzle orifice, a needle valve, and means for varying the relative position of the tip and nozzle dependent on the operation of the needle valve, and for providing an air inlet between said nozzle and tip when the needle valve is in a slightly retracted position.

4. A hydraulic nozzle construction including a main nozzle, a tip associated therewith, said nozzle and tip each provided with an aligned orifice, the walls of the nozzle orifice

converging toward the discharge end of said orifice and the walls of the tip being substantially parallel, the inlet end of the tip being of a diameter not less than the diameter of the discharge end of the nozzle, a needle valve within the nozzle for controlling the fluid passing therethrough, and means for varying the relative position of the nozzle and tip to provide an air inlet between the same on the movement of the needle valve forwardly within the nozzle.

5. A hydraulic nozzle construction including a main nozzle, a tip associated therewith, said nozzle and tip each provided with an aligned orifice, the walls of the nozzle orifice converging toward the discharge end of said orifice and the walls of the tip being substantially parallel, a needle valve within the nozzle for controlling the fluid passing therethrough, and means for automatically varying the relative position of the nozzle and tip to provide an air inlet between the same on the movement of the needle valve forwardly within the nozzle.

25 6. A hydraulic nozzle construction including a main nozzle, a tip associated therewith, said nozzle and tip each provided with an aligned orifice, the walls of the nozzle orifice converging toward the discharge end of said orifice and the walls of the tip being substantially parallel, a needle valve within the nozzle for controlling the fluid passing therethrough, and means for automatically varying the relative position of the nozzle and tip with the orifices maintained in alignment to provide an annular air inlet between the nozzle and tip, dependent on the position of the needle valve within the nozzle.

7. A hydraulic nozzle construction including a main nozzle, a tip associated therewith, said tip and nozzle each provided with a bore and said bores being disposed in axial alignment, a needle valve within the main nozzle for controlling the fluid flow therethrough, means for supporting the tip relatively to the nozzle discharge orifice, and means for moving the tip to and from the nozzle with the orifices maintained in alignment to provide an annular air inlet between the cooperating ends of said nozzle and tip.

55 8. A hydraulic nozzle construction including a main nozzle, a tip at its outer end, said tip and nozzle each provided with an orifice and said orifices being disposed in alignment, the walls of said nozzle orifice being of a true needle nozzle form and the walls of said tip orifice being of a true open nozzle form, and means for moving the tip to and from the outer end of the nozzle orifice, to afford an air inlet between the cooperating ends of the two orifices, the cooperating ends of said main nozzle and tip adapted for abutting contact with their orifice walls forming a symmetrical outlet.

9. A hydraulic nozzle construction consisting of two parts, a main nozzle part and a movable tip at the outer end thereof in contact therewith, said parts each provided with a discharge orifice arranged in alignment, a needle valve for controlling the fluid flow therethrough, and means for automatically adjusting said parts with their orifices in alignment and affording an air inlet between the same dependent on the position of the needle valve.

10. A hydraulic nozzle consisting of two parts, a main nozzle and a tip at the outer end thereof, said parts each provided with a discharge orifice arranged in alignment, a needle valve within the main nozzle for controlling the fluid flow therethrough, the walls of said orifices being respectively of true needle nozzle form and of true open nozzle form, and means for automatically adjusting said parts with their orifices in alignment and their adjacent ends in spaced relation to afford an air inlet between the same.

11. In combination with a hydraulic nozzle, a needle valve movably mounted therein to control the stream flow issuing from the orifice thereof, a tip at the discharge end of the nozzle and formed with an orifice of a contour differing from that of the nozzle orifice, and means for moving the tip to and from the end of the nozzle, the inlet end of the tip being of a diameter not less than the diameter of the discharge end of the nozzle.

12. In combination with a hydraulic nozzle, a needle valve movably mounted therein to control the stream flow issuing from the orifice thereof, a tip at the discharge end of the nozzle and formed with an orifice of a contour differing from that of the nozzle orifice, and means for moving the tip outwardly from contact with the nozzle to afford an air inlet between cooperating ends of said orifice, the inlet end of the tip being of a diameter not less than the diameter of the discharge end of the nozzle.

13. In combination with a hydraulic nozzle, a needle valve movably mounted therein to control the stream flow issuing from the orifice thereof, a tip at the discharge end of the nozzle and formed with an orifice of a contour differing from that of the nozzle orifice, a pair of pistons operatively supporting said tip in position, a cylinder within which each piston operates, a fluid pressure supply connected with opposite ends of each cylinder, a valve for controlling the pressure flow through said connection, and a valve trip adjustably mounted on the needle valve stem for actuating said valve, dependent on the position of the needle valve.

14. In combination with a hydraulic nozzle, a needle valve movably mounted therein to control the stream flow issuing from the

orifice thereof, a tip at the discharge end of the nozzle and formed with an orifice of a contour differing from that of the nozzle orifice, means for guiding said tip in its movement, an operating piston associated with the tip for moving the same, a piston cylinder, a pressure connection with the

cylinder, a controlling valve within said connection, and means for operating the controlling valve, dependent on the position of the needle valve.

In testimony whereof I have signed my name to this specification.

CHESTER B. McAULAY.
